MOP OR THE LIKE

William Hertzberg, New York, N. Y.

Application October 31, 1942, Serial No. 464,013

1 Claim. (Cl. 15—148)

This invention relates generally to the art of cleaning and more particularly to a novel cleaning implement.

Among the principal objects of this invention lies the provision of a combination duster and polishing mop of novel construction, presenting a high degree of utility and adaptability for different cleaning and/or polishing operations.

A still further object lies in a device of the class described in which the duster element thereof acts as a cushioning support of the polishing or mop element thereof.

Another object herein lies in the provision of a novel combination duster and mop which is readily converted from one type of operation to another and which by reason of the detachable interengagement of the parts may be readily dismantled for cleaning or specific uses.

Another object herein lies in the provision of a device of the class described in which the use of metal in the fabrication thereof is reduced to a minimum and which uses a relatively large proportion of material not needed for war or defense purposes.

A feature of the invention lies in the arrangement of rows of duster elements thereon which permits the ready infiltration of cleaning solvents for the renewing of usefulness of the device after it has become laden with soil.

An advantage of the present invention lies in the fact that the device is very easily maneuverable so that it may be used for a great variety of cleaning and polishing purposes.

By reason of the simplified construction thereof, this invention may be economically produced on a large scale at low cost, so that it may have a consequent wide sale, use and distribution.

These objects and other incidental ends and advantages will more fully appear in the progress of this disclosure and be pointed out in the appended claim.

In the drawing, constituting a material part hereof, similar reference characters designate corresponding parts throughout the several views in which:

Figure 1 is a front elevational view, partly in section, showing a preferred embodiment of the invention.

Figure 2 is a side elevational view showing the device of Figure 1, and is partly broken away so as to show some of the parts in vertical section.

Figure 3 is a fragmentary front elevational view of the duster element partly broken away to show some of the parts in section.

Figure 4 is an enlarged vertical sectional view as might be seen from the plane 4—4 on Figure 3.

Figure 5 is a transverse horizontal sectional view as seen from the plane 5—5 on Figure 1.

5 In accordance with the invention the cleaning implement generally indicated by numeral 10 includes a handle 11, a duster element 12, and a mop element 13.

The duster element 12 is preferably constructed 10 by engaging between a pair of spaced and parallel wires 14 and 15 a plurality of duster members 16. The wires are preferably composed of a material not deleteriously affected by water or other solvent materials commonly used in the cleaning operations. I have found that galvanized steel, or brass are good materials for this purpose. Stainless steel, or Monel metal may also be used. The duster members are preferably composed of cotton fibres of long staple which may

15 be in the form of a continuous wick or roving which is cut to lengths substantially slightly greater than the diameter of the duster element, taken through the wires 14 and 15. The wires 14 and 15 are twisted together (see Figure 3) 20 tightly compressing the center portions of the duster members 16 between them and securing the duster members in place. The wires 14 and 15 are preferably greater in length than twice the length of the duster element so that the wires as they

25 emerge from the ends 19 of the duster element are bent upon themselves to form return portions 17 and 18. The return portions are parallel to the center duster members securing portion 29 and are spaced therefrom a distance substantially 30 less than one-half the length of the duster members. This results in the concealment of the return portions 17 and 18 by the duster members 16 and in the use of the duster element 12 prevents these metal parts (16 and 17) from contacting 35 the article being dusted. The inner opposed ends of the return portions 17 and 18 are bent upon themselves at right angles to extend upwardly to form the duster element supporting shank 21.

40 The handle 11 may be of any suitable construction and is preferably in the form of a wooden rod having a ferrule 22 and an upwardly extending central orifice 23. The diameter of the orifice 23 is preferably slightly less than the greatest total diameter of the two ends of the return portions 17 and 18, as they form the shank 21. The duster element may thus be positively secured to the handle 11 by inserting the shank 21 into the orifice 23.

45 Turning now to the mop element 13, this is in 50 55

Turning now to the mop element 13, this is in

the form of an envelope. The mop element includes a first panel 24 and a second panel 25. The panels 24 and 25 are preferably composed of a woven fabric having a high degree of absorbency and of sufficient thickness and tightness of weave to maintain the shape thereof. The panels 24 and 25 are preferably rectangular in shape and are joined continuously along the abutting edges 26 and 27 thereof.

This construction may be readily effected by folding a single piece of cloth along the medial transverse axis thereof and by the installation of two separate continuous rows of stitching 29 and 30.

At the upper portions thereof, the mop element is provided with a handle receiving orifice 28. Since the orifice 28 is subject to a certain amount of wear, it may be reinforced by a suitable tape edging (not shown) well known in the art to which the present invention relates. The outer surfaces of the panels 24 and 25 are provided with spaced and parallel rows 35 of mop members 31. The mop members are preferably composed of aligned rows of transversely arranged wicking or yarn pieces, each row being secured in place upon the outer surface of said panels by a line of stitching 32, which engages the medial portions of said pieces. By reason of the soft and fluffy nature of the mop members 31, and the fact that they are relatively tightly packed on the surface of the panels, the ends of the mop members in one row intermingle with those of another row to form the working surfaces 33 and 34 on the panels 24 and 25. These working surfaces are highly absorbent so that they may act in both cleaning or polishing capacities. The vertical positioning of the rows 35 of mop members 31 forms channels 36 (see Figure 1) through which cleaning solvents may readily pass when the mop element is laundered for reuse after it has become laden with soil.

Operation

When the device is used for dusting small surfaces or intricately shaped pieces, the mop element is removed by passing the same upwardly over the handle 11. The duster element 12 has a relatively straight cylindrical bottom surface which may be used in a squeegee manner as well as relatively pointed bent ends 19 which may be poked into the crevices of radiators, Venetian blinds, stair tread corners, and the like. When it is desired to either dust or polish large surfaces such as walls, floors and the like the mop element may be placed so as to encase the duster element by pushing the mop element down over the handle 11 so that the handle penetrates orifice 28. The mop element is maintained in operative position both by gravity and by a certain amount of friction which takes place by compression between the ends 19 of the duster element 12 and the ends 38 of the duster members on one hand, and the inner surfaces 39 and 40 of the upper portions 41 and 42 of the panels 24 and 25 on the other hand. The duster element acts as a cushioning or resilient support for the upper portions 41 and 42, said upper portions being thereby given a rounded external contour

which is not only effective for cleaning similarly shaped areas but also prevents damage which might otherwise occur by hard portions within the duster element striking against chair legs, table legs and the like.

The lower portions 43 and 44 of the mop element 13 are relatively flexible and this flexibility is limited solely by the stiffness of the panels 24 and 25. Thus as the cleaning implement 10 is used with the mop element in place, when the device is drawn or pushed over a surface being treated, the flexible lower portions 43 and 44 may undulate to conform to said surface so that the same may be easily cleaned, waxed or polished.

Obviously the present device may be used dry, wet with water or wet with any other desirable solutions, such as sulfonated alcohol cleaning solutions or other well known detergents. Where desired either the duster element or the mop element or both may be impregnated with any suitable oils or waxes or combinations thereof.

It may thus be seen that I have provided a novel and economical cleaning instrument which is extremely versatile. Not only may this device be adapted for various types of cleaning or polishing operations but also with articles having various shapes and sizes.

By reason of the separable construction thereof, the mop element may be easily and quickly removed from the duster element. Since the mop element 13 is completely removable from the combined handle and duster element, where it is desired to dust or polish a relatively fragile article, the mop element may be used as a mitt by placing the user's hand upwardly through the bottom opening 50.

I wish it to be understood that I do not desire to be limited to the exact details of construction shown and described, for obvious modifications will occur to a person skilled in the art.

I claim:

A combination cleaning instrument comprising: an elongated duster element having a projection extending at the center of said duster element and at right angles thereto to form a handle; a mop element composed of a single sheet of material of greater length than the transverse periphery of the duster element, said sheet being folded upon itself about its transverse medial axis to form a straight top portion; said top portion having a central orifice disposed in said axis; the opposed free longitudinal edges of said sheet being interconnected by vertical rows of stitches; the free lower transverse edges of said sheet and the portions thereof contiguous thereto being flexible and free of contact with said duster element; absorbent mop members on the exterior surfaces of said mop element; said duster element in the engaged position thereof being insertable between the unconnected free transverse lower edges of the mop element, said projection being passable through said orifice, the duster element forming a cushion support for the upper portion of the mop element; said duster element in the disengaged position thereof, being itself separately usable; and the mop element being separately usable as a cleaning mitt.

WILLIAM HERTZBERG.
